UNITED STATES PATENT OFFICE

GEORGE ROLLO HARRIS, OF LOS ANGELES, CALIFORNIA

DESIGN FOR A STREET-LIGHTING FIXTURE

Application filed August 5, 1929. Serial No. 32,307. Term of patent 3½ years.

To all whom it may concern:

Be it known that I, GEORGE ROLLO HARRIS, a citizen of the United States, residing at Los Angeles, in the county of Los Angeles and State of California, have invented a certain new, original, and ornamental Design for a Street-Lighting Fixture, of which the following is a specification, reference being had to the accompanying drawings, forming a part thereof, in which the figure shown is a side elevational view of my new,

original, and ornamental design for a street lighting fixture separate and apart from its supporting means.

I claim:

The ornamental design for a street lighting fixture, substantially as shown.

In testimony whereof, I have hereunto set my hand at Los Angeles, California, this 10 day of July, 1929.

GEORGE ROLLO HARRIS.
